UNITED STATES PATENT OFFICE.

JOHN W. FOSTER, OF WESTFIELD, MASSACHUSETTS, ASSIGNOR TO THE FOSTER MACHINE COMPANY, OF SAME PLACE.

SPOOLING-MACHINE.

SPECIFICATION forming part of Letters Patent No. 585,198, dated June 29, 1897.

Application filed March 19, 1896. Serial No. 583,908. (No model.)

To all whom it may concern:

Be it known that I, JOHN W. FOSTER, of Westfield, county of Hampden, State of Massachusetts, have invented an Improvement 5 in Spooling-Machines, of which the following description, in connection with the accompanying drawings, is a specification, like letters on the drawings representing like parts.

This invention has for its object to improve 10 spooling-machines, whereby the yarn or thread of cotton, wool, or silk may be wound more rapidly.

The machine is provided with a drop wire or lever to actuate a leg-lever or other device 15 of a stop-motion mechanism when a yarn or thread breaks or becomes too slack, and I have combined with this drop wire or lever devices to automatically lift it in position to be rethreaded. I have also provided novel 20 means for insuring the delivery of the yarn or thread from the end of the spool supplying the same to be wound on a conical or other shaped tube or holder, and the spindle carrying said spool may be rotated very slowly, if 25 desired, to prevent any loss of twist in unwinding the yarn or thread from the end of the spool.

Figure 1, in side or end elevation, shows a sufficient portion of a spooling-machine to 30 enable my invention to be understood, the support for the spindle carrying the spool being broken out and the spindle being shown as moved inwardly toward the center of the machine out of its true working position, with 35 its end under the usual guide-eye, to thus save space on the drawings, the cone on which the thread is to be wound being omitted. Fig. 2 is an enlarged section of the spindle, spool, and spindle-cap; Figs. 2^a and 2^b, details to be described; Fig. 3, a detail showing 40 the face of the drum, a cone-holder and cone, and the yarn or thread guide and its support, the guide being actuated by the groove of the drum, the winding-roll and its carrying-arms 45 being omitted. Fig. 4 is an enlarged detail showing part of the drum with its peculiar-shaped groove and traveler of the yarn or thread guide arranged therein; and Fig. 5 shows, detached from Fig. 1, the yarn or 50 thread guide and the reversing-spring.

The frame A, of suitable shape to contain

the working parts, has a shaft A', on which is mounted a drum A² or a series of drums having each a groove running diagonally about it for the reception of a traveler from 55 a thread-guide to be described, the said drum or drums being of such size as to wind a conical or straight cop-tube at each side thereof, as in United States Patent No. 535,616, granted to me, and dated March 12, 1895. 60

Fig. 3 shows a yoke or carrier w, such as may be used to hold a conical shell r, on which the yarn or thread may be wound.

I will first describe my improvements in the drum. 65

It is an object in this class of machines to make the drum as light and thin as possible, and heretofore the periphery of the drum has been of uniform thickness and has been provided with a shallow groove extended about 70 the drum, in which entered a shallow traveler connected to the thread-guide. These machines are run at a high speed, for it is a great desideratum to spool the greatest number of yards of yarn or thread possible in a 75 given time. I have found in practice that the practical speed of the drum is limited to the strength of the traveler and the rapidity with which the thread-guide may be reciprocated without breaking. The larger the diameter of the drum the greater its surface speed and the faster it will rotate a cop and the more yarn or thread it will wind on a cop-tube at each rotation. 80

Heretofore the practical diameter of the 85 drum has been found to be twelve inches, and the thread-guide will run practically in a groove in the surface of such a drum. I have found it practicable to use a drum of thirteen and three-eighths inches diameter. 90

It will be remembered that the surface of the drum travels at the fastest speed and that as one approaches the center of motion thereof the speed of movement of the parts of the drum decreases. 95

To enable me to actuate the thread-guide a to be reciprocated at the usual practical speed which is effected by a twelve-inch drum and yet increase the speed of rotation of the cop to a speed which would be derived from 100 the surface velocity of, say, a drum for thirteen and three-eighths inches in diameter, I

have provided the inner side of the periphery of the drum with a rib a' and, as best shown in Fig. 5, I have cut a groove through said drum and into the rib, leaving in the rib side walls located at a distance, say, of substantially one and three-eighths inches from the periphery of the drum, and into this groove I have placed the traveler a^3 , its carrying-pin a^4 being extended into a hub a^5 of the thread-guide carrier a^20 , which hub enters a wider part of the groove in the periphery of the drum, the hub preferably not touching the walls of the groove in said periphery. In this way the slower moving part of the drum—viz., the side walls of the groove in the rib—acts frictionally against the traveler a^3 , and said side walls, traveling at a slower speed than the side walls of the groove in the periphery of the drum, act in greatly reducing the friction and wear on the traveler.

In the old form of drum the traveler could not be oiled, because the oil escaped to the outside of the drum and was taken up on the winding-roll s , lying against the drum, and was by it put onto the yarn or thread, soiling it.

To enable the traveler employed by me to be oiled and thus greatly reduce its friction when being moved, I have provided each inner side wall of the groove in the rib with a like oil pocket or groove a^6 , having its mouth a little wider than its bottom, and I have provided the bottom of each of said grooves with suitable ejection-holes a^7 , said holes being outwardly inclined, as shown best in Fig. 4, so that oil put into the groove in which the traveler runs will by centrifugal action be forced into the pockets, and if too much oil will issue through the holes a^7 onto the interior of the drum, where it will do no harm and can be wiped off from time to time.

The thread-guide carrier a^20 runs on a bar a^8 , held in suitable supports b , and lest the blow of the groove in reversing the thread-guide should be too hard I have combined with the bar and guide a suitable spring h , (see Figs. 1 and 6,) against which the ends of the guide strike at the ends of its stroke, the said spring taking the shock of the stroke of the guide, thus relieving the traveler and its pin and starting the thread-guide, so that it will quickly commence its return stroke with the minimum of strain on the traveler, so that the latter is not worn and the pin not strained and will run for a very long time.

The arms b support a rock-shaft b^2 , having upwardly-extended arms b^3 , which have open forks to receive the winding-roll s , which acts just as in the patent referred to, said shaft having a depending arm b^4 , to which is jointed at b^5 a bar b^6 , fitted into a guide-box b^7 , the bar having at its under side a suitable projection b^8 , with which co-operates a spring b^9 , having, preferably, two holding-recesses, in one or the other of which said projection will rest. This bar has pivoted on it a lever h^8 , the inner or heavier end of which is normally

down, as in Fig. 1, the said lever having a hook which is acted on when raised by one of the teeth of a ratchet m , fast on a rotating shaft m' common to said patent, but designated by different letters.

The yarn or thread g is led from a spool c , to be described, through a guide-eye c' , over a beam c^2 , thence through an eye in the drop-lever c^3 , connected to a collar c^4 , loose on a stud c^5 , held in an ear rising from the arm c^6 , said collar having a toe c^7 .

The yarn or thread is led from the drop-lever to the thread-guide a , and the lever is held by the thread with its eye above the top of the drop-lever guide c^7x ; but when the yarn or thread breaks the drop-lever descends and strikes the front end of the lever h^8 , causing its other end to be engaged by the stop-wheel m , such engagement of the lever causing the bar b^6 to be slid to the right in Fig. 1, turning the rock-shaft b^2 in the direction to remove the winding-roll from the drum. I utilize this movement of the rock-shaft to reset the drop-lever, for I have connected to the arm b^4 of the rock-shaft a rod d , attached at its other end to a lifting device d' . (Shown in Fig. 2^a as a yoke having ears to span the ear of the arm c^6 , the ears having holes to receive the pin c^5 .)

As the rod d is drawn to the right the under side of the lifting device acts on the toe c^7 and turns the collar in the direction to lift the eye end of the drop-lever above the guide c^7x , leaving it in position to be rethreaded and obviating the necessity of the operator engaging the drop-lever to lift it by hand.

I have connected the upper ends of the arms b^3 by a bar d^3 , and on one of the caps d^4 , used to hold the bar a^8 in Fig. 1, I have placed a stud d^5 , on which I have mounted a starting-lever d^6 , the upper short cam-shaped end of said lever (see Fig. 2^b) being adapted when the lever is moved by the operator in the direction of the arrow in Fig. 2^b to act on the bar d^3 and turn the rock-shaft b^2 in the direction to cause the winding-roll to again contact with the drum and be rotated to recommence the winding.

The spool c rests on a grooved collar e of a whirl e' , surrounding loosely a dead-spindle e^2 , the end of the whirl being reduced in diameter and resting on a stop e^3 .

The whirl has above its grooved collar e an extension e^4 , which has fixed to it a tubular sleeve e^5 , extended up through and above the top of the spool, where the upper end of the tube (see Fig. 2) receives upon it and supports clear of the spool a metal cap e^6 , having a circular flange e^7 to overlap and inclose the head of the spool. The spool fits the tube loosely, and the yarn or thread is led up or off from the end of the spool, it during its delivery running or traveling about the edge of the cap.

I may, if desired, provide the groove of the collar e with a band e^8 , driving the same slowly from any suitable moving shaft of the

machine (not shown) as spindle-driving bands are now driven, said band rotating the spool slowly to thus obviate taking out any of the twist in the yarn.

5 The spring h (see Fig. 5) is connected to a block h' , fast on the rock-shaft b^2 , but this invention is not limited to the exact shape shown for the said spring, and the shape may be varied without departing from my invention.

The thread-guide a is pivoted on the carrier a^2 and is slotted at its upper end and is of such length that when the winding-roll s is thrown away from the drum to stop winding the said roll will act against the pivoted thread-guide and turn it outwardly far enough to cause it to release the thread and leave it lying on the top of the bar and roll, so that as the traveler continues to slide back and forth the thread-guide does not move the thread with it. The dotted lines t^4 above the roll s show the position of the tube or holder and the yarn being wound on it.

The spool surrounds the tube e^5 loosely, so that the spool may turn freely on the tube on the occurrence of any strain on the yarn.

Having described my invention, what I claim as new, and desire to secure by Letters Patent, is—

3c 1. In a spooling-machine, a shell-like drum having an internal diagonal rib, provided with a diagonal groove in prolongation of a diagonal groove extended entirely through the thickness of said drum, the side walls of 35 the groove in said rib presenting traveler-actuating surfaces wholly within the thickness of the body of said shell, combined with a thread-guide support, a thread-guide, and its connected traveler, the latter being actuated by the side walls of the groove in said 40 rib, substantially as described.

2. In a spooling-machine, a drum having an internal diagonal rib provided with a groove for the reception of a traveler connected to the 45 thread-guide, the inner walls of said groove having oil-receiving pockets, said pockets having ejection-holes for the oil, combined with a thread-guide and its traveler actuated by the walls of the groove in said rib, substantially as described.

3. In a spooling-machine, a drum having at its interior a diagonal rib, the said drum and rib being each grooved, the groove in the rib being enlarged near the inner side of the drum 55 to provide pockets, a bar, a thread-guide free to be moved thereon and a traveler connected to the thread-guide, the traveler entering the groove in the rib inside the periphery of the drum, substantially as described.

6c 4. In a spooling-machine, a drum having at its interior a diagonal rib, the said drum and rib being provided with grooves, a bar, a thread-guide free to be moved thereon and provided with a traveler, the traveler entering 65 the groove in the rib inside the periphery of the drum, combined with a spring to arrest the thread-guide at the end of its stroke

and reduce the strain on the traveler connected to the thread-guide, substantially as described.

5. In a spooling-machine, a drop-lever having an eye to hang on the thread, a guide in which it plays, and a stop mechanism actuated by the dropping of the drop-lever, and means connected with said drop-lever to cause it 75 when released to automatically lift the drop-wire into position again where it may be re-threaded, substantially as described.

6. The drum, the winding-roll actuated by it, a rock-shaft having arms to carry said roll, 80 an arm b^4 attached to said rock-shaft, and a collar and its attached drop-lever combined with means between said arm and collar to lift the drop-lever as the said arm is moved in the direction to remove the winding-roll 85 from contact with the drum, substantially as described.

7. The drum, the winding-roll adapted to be rotated by said drum, a rock-shaft having arms provided with bearings for the journals 90 of said roll, a connecting-bar d^7 uniting said arms, and a stand, combined with a lever pivoted on said stand and provided with a cam-shaped end to act on the said connecting-bar when the said lever is turned in one direction 95 to put the winding-roll in contact with the said drum, substantially as described.

8. In a spooling-machine, a spindle, a sleeve-whirl having a collar grooved externally for the reception of a band and surrounding said spindle loosely, a tube attached to said sleeve-whirl, a step to support one end of said sleeve-whirl, a cap applied loosely to the upper end of said spindle and supported wholly by the end of said tube leaving a space between said collar and the upper end of said tube for the reception of a spool, and a band to rotate said sleeve-whirl slowly, combined with a drum, a thread-guide reciprocated thereby, and a winding-roll to receive the 100 thread from the spool on said spindle, the thread from said spool on said spindle passing over the edge of the cap, the rotation of the said sleeve-whirl during the delivery of the thread from it keeping the twist uniform, 105 substantially as described.

9. In a spooling-machine, a drum having at its inner side a diagonal rib, the said drum and rib being grooved to leave side walls to act against a traveler at a point within the 110 inner side of the periphery of the drum, combined with a winding-roll to rest against the face of the drum, a bar, and a thread-guide thereon having an attached traveler extended through the slot of the drum and into the slot 115 in the rib inside the drum, whereby the winding-roll is actuated by the fastest moving part of the drum and the traveler by a much slower moving part of the drum, substantially as and for the purpose described.

10. In a spooling-machine, a winding-drum having an internal diagonal rib grooved for the reception of a traveler, and having side walls located in said groove within the 130

periphery of said drum, combined with a thread-guide having an attached traveler which is acted upon by the side walls of the groove in the said rib, whereby the traveler is actuated by a surface moving more slowly than the periphery of said drum, substantially as described.

11. In a spooling-machine, a drum, a winding-roll actuated thereby, and a reciprocating thread-guide carrier having a pivoted thread-guide mounted thereon, combined with a bar toward which the thread-guide is turned by the winding-roll as the latter is

moved away from the drum to automatically stop the winding operation, the said bar receiving upon it the thread from the thread-guide as the latter is turned back and removed from the thread, substantially as described.

In testimony whereof I have signed my name to this specification in the presence of two subscribing witnesses.

JOHN W. FOSTER.
